RAILWAY PREFERENCE TRAFFIC SIGNAL
CONTROL

Frank H. Richterkessing, Louisville, Ky., assignor
to Nachod & United States Signal Company,
Incorporated, Louisville, Ky., a corporation of
Kentucky

Application December 19, 1927, Serial No. 241,114

10 Claims. (Cl. 177—337)

My invention relates to the vehicular control of an automatic traffic signal, and is primarily intended for use at the intersection of two thoroughfares, on one of which is operated an electric street railway.

The main object of my invention is to provide a system wherein the indications of a signal controlling intersecting traffic are normally displayed periodically; but, with the approach of an electric street car within a selected zone, the periodic display of the traffic signal indications is interrupted and the proceed indication displayed to the said street car to expedite the preferential movement of the car until it passes the intersection, whereupon the said traffic signal indications are restored to their normal periodical control.

The purpose of such an arrangement is to permit street cars to have a continuous movement past points where signals controlling traffic are located, thereby eliminating the objection of having the said street cars make unnecessary stops at these intersections, and resultantly eliminate the traffic congestion that usually results from the slow movement of electric cars.

My invention resides in a new and novel combination, the construction and relation of various electrically operated switches, circuits and other parts hereinafter more fully described and disclosed in the drawing.

In the drawing accompanying this specification, the figure is a schematic drawing showing the electrical circuits of my system, and the relative location of the various control apparatus.

35 My invention is intended primarily to be controlled by cars that are operated with an overhead trolley wheel or current collector 3a, mounted on a car by means of a trolley pole T, although it may be controlled by vehicles that are operated by other methods.

In the system shown in the figure, the numeral 1 represents a trolley wire. Positioned adjacent this trolley wire 1, are trolley contactors 3, 4 and 5, which are normally insulated therefrom, but are electrically connected thereto when the current collector 3a engages the trolley contactors 3, 4, and 5 respectively. Trolley contactor 3 is mounted on the trolley wire 1 and is placed within a selected proximity on the east approach side of the intersection, represented in the drawing by N, S, E, W. Trolley contactor 4 is placed a distance in advance of trolley contactor 3 and on the approach side of the intersection equivalent to the time of amber indication. Contactor 5 is mounted on the trolley wire

on the far side of the said intersection. At the intersection the numeral 2 represents a signal periodically displaying Stop, Caution and Proceed indications for the W, E electric line traffic, and the N, S intersecting traffic.

The relay R2 that I employ is provided with two operating coils A and D, and each are energized to provide alternate operations of the contact arm A1. When a car passes the trolley contactor 3, the coil A is energized, and the contact arm A1 is shifted in the direction indicated by the arrow DA. When the car passes the trolley contactor 5, the coil D is energized, and the contact arm A1 is restored to its normal position. The contact arm A1 normally engages contact A2 and is brought into this position through the energization of the coil D. When the coil A is energized the contact arm A1 is shifted and disengages the contact A2 and is brought into contact engagement with the contact D1. The contact arm A1 is biased to either position through the toggle spring S1.

I also employ an electrically operated relay R1 which is provided with two operating coils B and C and each are energized to provide alternate operations of the contact arm B1. When a car passes the trolley contactor 4, the coil B is energized, and the contact arm B1 is shifted in the direction indicated by the arrow DB. When the car passes the trolley contactor 5, the coil C is energized, and the contact arm B1 is restored to its normal position. The contact arm B1 of relay R1 normally engages contact B2 of relay R1 and is brought into this contact engagement through the energization of coil C. When the coil B is energized, the contact arm B1 is shifted and is brought out of contact engagement with the contact B2 and into contact engagement with the contact C1. The contact arm B1 is biased to either position through the toggle spring S2.

In my system I also employ a means for periodically controlling the display of the indications of the traffic signal; that is, when the relays R1 and R2 are not influenced through the approach of an electric car, the indications of the traffic signal normally display in a predetermined sequence of a given cycle. This is the same form of signaling now almost universally accepted and used for controlling vehicular traffic. In the system shown in the figure, a very simple form of control is shown for the said periodical control of the traffic signal indications. This control consists of a motor driven time element device, TS that is equipped

with a series of segments and cams mechanically interconnected in a manner to control periodically and cyclically the circuits of the signal indications. Since the subject matter of my invention is not directed to the construction of this device, the device is illustrated as having a contact arm CA rotated by a motor M, which arm successively and cyclically engages contact segments GC, YC, RC and YC'.

The portion enclosed by the dotted line 2a in Fig. 1 is a symbolic representation of a traffic signal housing three decks of signal indications. Each deck is equipped with separate indications to be displayed in the four directions. In the upper deck, the red lenses 1R and 2R that face N and S and the green lenses 1G and 3G that face W and E, have a common light source represented by U. In the center deck the four lenses 1Y, 2Y, 3Y, and 4Y display an amber or caution indication and have a common light source represented by V. In the lower deck the green lenses 4G and 5G that face N and S, and the red lenses 3R and 4R that face E and W, have a common light source represented by Wa. For clarity, each of the three decks are shown in a plan view, and this must be taken into consideration when the signal system is described so that the proper signal indications will be given for the proper directions.

In the system, the indications of the traffic signal are normally displayed periodically, that is, each signal indication displays a certain predetermined time before the display of another signal indication occurs, all of which occurs in a definite sequence of a predetermined cycle. Starting for instance at an arbitrarily selected time of the cycle, we have the display of a green indication for the W, E electric line traffic, and the display of a red indication for the N, S intersecting traffic. The circuit for these indications is under the control of the segment GC of the automatic control device TS. With reference to the drawing, it will be noted that these indications will continue to display until the contact arm CA disengages the segment GC. Upon disengaging the segment GC, the contact arm CA engages the segment YC, resulting in a display of an amber or caution indication to all traffic, to warn the traffic that a change in the right-of-way is about to occur. It will also be noted that the amber indication will continue to display until the contact arm CA disengages the segment YC and comes into contact engagement with the cam segment RC, whereupon a reversal in the display of the right-of-way indications occurs; that is, a red indication is displayed for the W, E electric line traffic and a green indication for the N, S intersecting traffic. These indications will also continue to display as long as the contact arm CA engages segment RC, after which the arm CA will engage the segment YC' and again display the amber indications. Thus, with relays R1 and R2 in their normal positions, the motor-driven time-element device TS provides a cyclic display of the signal indications.

When the current collector 3a engages the trolley contactor 3, the coil A of relay R2 is energized, and the contact arm A1 is shifted in the direction shown by the arrow DA, bringing the contact arm A1 into contact engagement with contact D1 and out of contact engagement with contact A2. The circuit for the energization of coil A of relay R2 is completed from the trolley wire 1, through the current collector 3a, trolley contactor 3, wire b, coil A, wire O, to ground 2G.

As soon as the current collector disengages the trolley contactor, the coil A of relay R2 is de-energized, but the contact arm A1 remains in the shifted position. As soon as the contact arm A1 shifts, irrespective the display of the indications previously affected by the automatic control device TS, amber indications are displayed to warn the traffic that a change in the right-of-way is about to occur. The circuit for the amber indications is completed from the positive side, 10 the line BX110V, through wire f, contact arm B1 of contact B2, wire m, contact arm A1, contact D1, wire i to lamp V, which lamp is a common light source for the amber indications, through wire n2, wire n4, wire n, to the common 15 return of the line CX110V. If, however, the motor-driven time-element device TS was displaying the amber indications no immediate change would occur in the display of the traffic signal indications, since the display of the amber 20 would be continued under the influence of the control affected by the movement of the trolley car. After the car traverses a certain predetermined distance, the current collector 3a engages trolley contactor 4, whereupon the coil B of relay R1 is energized, and the contact arm B1 is 25 shifted into contact engagement with contact C1 and out of contact engagement with contact B2. This operation of relay R1 extinguishes the amber indications by opening the circuit 30 completed through the normally engaged contact B2 of relay R1, and displays a green indication for the W, E electric line traffic and a red indication for the N, S intersecting traffic. With reference to the drawing, it will be noted that 35 these indications will continue to display under the influence of relay R1, irrespective of the operation of the automatic control device TS. Thus, the car having received a proceed indication now continues past the intersection. After 40 the street car passes the intersection, the current collector 3a, engages trolley contactor 5, whereupon the operating coils C of relay R1 and D of relay R2 are energized, and the contact arms B1 and A1, respectively, are restored to 45 their normal positions. The circuit for energizing the coils C and D is completed from the trolley wire 1, through the current collector 3a, trolley contactor 5, wire K, operating coil C, wire Q, to ground 2G. It will also be noted that 50 the wire k connects two circuits, one as described, and the other thru wire r, operating coil D, wire P to ground 2G. Thus, since the energization of coils C and D restored the relays R1 and R2 to normal, the display of the traffic signal indications is restored to the automatic control device 55 TS.

There are, of course, modifications and arrangements that may be made from those shown in the above disclosure, which will still fall within the scope of my invention.

I claim:

1. In a traffic signaling system arranged at the intersection of a main highway and crossroad for regulating traffic, the combination with a 65 visual signal comprising a proceed indication, a caution indication and a stop indication for each thoroughfare, means for the routine display of said traffic indications to the said thoroughfares, trolley contactors to be engaged by a car in said 70 highway approaching and clearing the intersection, means for divesting the first said means of its normal function and energizing the said caution indication for both highways when one trolley contactor is engaged, and means to di- 75

vest the second said means of its function and energize the said proceed indication on the main highway and the said stop indication on the crossroad when a second trolley contactor is engaged, and means for restoring the routine display of the indications by the first said means when a third trolley contactor is engaged.

2. In a traffic signaling system for interfering traffic lanes, the combination with a right-of-way indicating device comprising a proceed indication, a caution indication and a stop indication for each traffic lane, means for the routine display of said traffic indications to the said traffic lanes, traffic responsive devices to be actuated by a vehicle on one of said traffic lanes, means for divesting the first said means of its normal function and energizing the said caution indication for both traffic lanes when one of said traffic responsive devices is actuated, and means to divest the second said means of its function and energize the said proceed indication on the traffic lane containing the said traffic responsive devices and the said stop indication on the other traffic lane when a second traffic responsive device is actuated; and means, operable by a vehicle on the said one lane, for restoring the routine display of the indications by the first named means.

3. In a street intersection traffic control signal system, in which a preferred street having an electrical vehicle thereon operating from a current supply feeder may take the right-of-way indication to the exclusion of the other street, including a plurality of signal lamps; signal timer means for normally cyclically displaying said signals to alternately give the right-of-way indication to the several streets; a vehicle current collector responsive device on the preferred street; super control means connected to be operated by the current collector responsive device when actuated by a vehicle on the preferred street to render said signal timer means ineffective to normally display said signals and to give a right-of-way indication to the preferred street; and means operated by the said vehicle on the preferred street to restore the normal display of the signals by the said signal timer means.

4. A traffic signaling system for regulating traffic on interfering traffic lanes, said system including a right-of-way indication for each of the said traffic lanes, switch means, circuit connections between the said switch means and the right-of-way indications, whereby the said switch means is rendered effective to alternately and repeatedly energize the said circuits, and means actuated by a vehicle on one of the said traffic lanes and approaching the said right-of-way indicating device to alter said electrical connecting means so that the said switch means is rendered ineffective, and the circuit connecting the right-of-way indication on the last said traffic lane is continuously energized, and a second means operable by the vehicle on the last said traffic lane to restore the said indications to their normal control.

5. In a traffic signaling system for interfering traffic lanes having, means for displaying right-of-way signal indications; signal-timer means for normally cyclically-displaying said right-of-way indications successively to the several traffic lanes; a first vehicle-responsive device on one of said lanes; super control-means, operable by response of said first device to a vehicle on said one lane, to render said timer means ineffective

to display normally said indications and to give the right-of-way indication to the said one lane; a second vehicle-responsive device on the said one lane; and control-means, operable by response of the said second device to a vehicle on the said one lane, to render the said timer means effective to display normally said indications.

6. A right-of-way indicating device for interfering traffic lanes; a constantly operating device, a controller means driven by the constantly operating device; circuit connections between the said controller and right-of-way indicating device, for normally cyclically shifting said right-of-way indication from one traffic lane to the other, other circuit connections to said right-of-way indicating device for a constant display of the right-of-way indication to one of the said traffic lanes, relay means activated by a vehicle for shifting from the first named circuit connections to the second named circuit connections whereby the normal cyclic display of the right-of-way indications is interrupted and the right-of-way indication to the last mentioned traffic lane is maintained, and means affected by the vehicle for restoring the said relay means to normal whereby the normal cyclic display of the right-of-way indication is restored.

7. A traffic signaling system for regulating traffic on interfering traffic lanes, said system including a right-of-way indicating device for each of the said traffic lanes, a constantly operating device, a controller means driven by the said constantly operating device, circuit connections between the said controller and right-of-way indicating device for normally cyclically shifting said right-of-way indications from one traffic lane to the other, means affected by a vehicle approaching the right-of-way indicating device on one of the said traffic lanes to interrupt the normal cyclic display of the said right-of-way indications and prolong the energization of the right-of-way indication on the last said traffic lane, and means affected subsequently by the vehicle for restoring the normal cyclic display of the said right-of-way indications.

8. A traffic-signaling system for interfering traffic lanes, comprising, stop and go signals for each of the said lanes; timer means having a plurality of switches operating in accordance with a predetermined cycle; circuit connections between the said switches and the said indications for a cyclic display of the said indications in accordance with the cyclic operation of the said switches; other circuit connections for the said indications for a constant display of the go indication on one lane and the stop indication on all other lanes; a vehicle-actuated device for the said one lane; means operating in response to an actuation of the said device for shifting the said stop and go signals from the first named circuit connections to the second named circuit connections for interrupting the cyclic display of the said indications by the said switches and establishing the said constant display of the go signal on the one lane and the stop indications on all other lanes; a second vehicle-actuated device for the said one lane; and means operated by the actuation of the said second vehicle-actuated device for shifting from the said second named connections to the said first named connections for restoring the cyclic display of the said indications by the said switches.

9. A traffic control system for intersecting traffic lanes having, in combination, a first signal-

ing-means for directing traffic to proceed on one lane and for restraining traffic on the intersecting lane; a second signaling-means for directing traffic to proceed on the said intersecting lane and for restraining traffic on the said one lane; operating circuits for the said first and second signaling means; signal timer-means operatively associated with the said operating circuits for alternately and repeatedly opening and closing the said circuits, thereby to energize alternately and repeatedly the said first and second signaling means; an auxiliary normally-open circuit for the said first signaling means; a traffic-actuated device in the said one lane; relay means, operable in response to an actuation of the said traffic-actuated device, for opening the said operating circuits and closing the said auxiliary circuit, thereby to discontinue the alternate and repeated energization of the said first and second signaling means by the said timer means, and to energize directly the said first signaling means; and means operable to restore the alternate and repeated energization of the said first and second signaling means by the said timer means.

10. A traffic control system for intersecting traffic-lanes having, in combination, a first signaling-means for directing traffic to proceed on one lane and for restraining traffic on the intersecting lane; a second signaling-means for di-

recting traffic to proceed on the said intersecting lane and for restraining traffic on the said one lane; operating circuits for the said first and second signaling means; signal timer-means operatively associated with the said operating circuits 5 for alternately and repeatedly opening and closing the said circuits, thereby to energize alternately and repeatedly the said first and second signaling means; an auxiliary normally-open circuit for the said first signaling means; a first 10 traffic-actuated device in the said one lane constructed and arranged to be actuated by a vehicle approaching the intersection; relay means, operable in response to an actuation of the said first traffic-actuated device, for opening the said operating circuits and closing the said auxiliary circuit, thereby to discontinue the alternate and repeated energization of the said first and second signaling means by the said timer means, and to energize directly the said first signaling means; 15 a second traffic-actuated device in the said one lane adjacent the said intersection; and means operable in response to an actuation of the said second traffic-actuated device, for restoring the alternate and repeated energization of the said first and second signaling means by the said timer means.

FRANK H. RICHTERKESSING.
